UNITED STATES PATENT OFFICE.

EDWARD S. BEACH, OF RIDGEFIELD, CONNECTICUT.

MOTOR-TRICYCLE.

1,139,835.

Specification of Letters Patent. Patented May 18, 1915.

Application filed October 24, 1914. Serial No. 868,376.

To all whom it may concern:

Be it known that I, EDWARD S. BEACH, a citizen of the United States, residing at Ridgefield, in the county of Fairfield and State of Connecticut, have invented certain new and useful Improvements in Motor-Tricycles, of which the following is a specification.

This invention relates to motor tricycles. 10 The objects of the invention are low cost coupled with durability of construction; and if desired, to adapt the car particularly for use of campers. This motor tricycle may be of standard tread width or of a 15 narrower tread width if desired, and is intended to carry one or more persons tandem or otherwise, or conveniently to carry one person and goods, etc., for delivery. This new motor tricycle is also useful as a motor 20 tractor.

In the drawings the invention is embodied in an elongated, under-slung, motor tricycle.

In the drawings forming a part hereof, Figure 1 is a side elevation of the car, one 25 form of body being indicated by dotted lines. Fig. 2 is a top plan view with the rear canopy or tent-supporting, folding-posts omitted for greater clearness. Fig. 3 is a front elevational view, the body being 30 omitted. This view particularly illustrates the construction and assemblage of a spring-bearing fork and the wheel-bearing fork, one-half of the forks being in vertical central section. Fig. 4 is a top plan view, partially in section, of the assembled forks, at 35 line 4-4 of Fig. 3. Fig. 5 is a top plan view of the wheel-fork detached. In Figs. 4 and 5 a portion of the wheel carried by the wheel-fork is indicated.

40 In the drawings, 1 is a spring-supporting fork formed at the lower end of each leg with a laterally-extending spring-supporting foot 2 and at the inner side of its crown with a flat bearing 3, and through the crown 45 with a hole at 4. The ends of the feet are preferably but not necessarily supported by braces 5 the lower ends of which are pinned to the feet at 6, and the upper ends of which are pinned to opposite sides of the spring- 50 supporting fork at 7. If unduly heavy loads are to come on the feet, as in heavy

car construction, it is desirable to brace the extremities of the feet against downward deformation. The heel portions of the legs of the spring-supporting fork are each recessed to form opposite wheel-fork bearings 8, each of these bearings having its outward dependent wall 8^a arched on a center of a circle struck from the lengthwise axis of the fork. 55

The wheel-fork supports at the lower ends of its legs 9 an axle 10 for the wheel W, each leg 9 having an outwardly and laterally projecting arched foot 11 to fit in a bearing 8 of the spring-supporting fork. The crown 65 of the wheel fork is provided with a journal extension 9^a which fits loosely in the bearing hole 4, the spring-supporting fork having at the base of the extension 9^a a flat bearing 9^b contacting with the bearing 3 of the fork 70 1. Journal extension 9^a extends through the crown of fork 1, and is threaded to receive a bearing nut 12. An under bearing plate 13 for each wheel-fork foot is detachably connected at 14 to each foot of the spring- 75 supporting fork, and the wheel-fork feet are preferably formed with vertical holes for reception of screws x which pass through recesses in the axle 10 to keep the latter from rotation and endwise movement, 80 as indicated in Figs. 4 and 5 where the peripheries of the screws are shown projecting into the path of the axle which is shown in dotted lines. By the described construction of the forks, the wheel fork 85 has at its upper end and also at its under end, both an end-thrust bearing and a lateral bearing on the spring-supporting fork, thereby minimizing lateral strains tending to produce a wabbling of the fork-wheel 90 when in use.

Each foot of the spring-supporting fork has a spring 15 secured to it at 16. In the form shown, the assembled forks are at the front end of the tricycle and the springs 15 95 are conveniently referred to as front springs; but it is to be understood that the single wheel W might form the rear wheel of the vehicle according to known practice in motor tricycle construction. The front 100 springs 15 are parallel and extend toward the rear driving axle 17 provided with fixed

wheels W'. Axle 17 supports at 17^a a pair of parallel springs 18 in suspension, the front ends of the springs 18 extending toward the front springs and the rearward 5 ends of springs 18 extending rearwardly beyond the driving axle.

To the rearward end of each front spring a side-bar 19 is suitably connected by connections 20 which also support a transverse 10 bar 21; and by connections 22 which support a transverse bar 23. The front ends of the rear springs are shackled to the side-bars at 24 and the rear ends of the rear springs are pivoted at 25 each to an upstanding bracket 26 carried by a side bar 19, these side bars being united by transverse bars 27 which form a foundation for the motor M rearward of the rear or driving axle. The motor shaft extends transversely of the vehicle parallel with the driven axle, and has an end *m* accessible at one side of the under frame for cranking the engine rearwardly of one of the rear wheels.

The motor shaft is operatively connected 25 with the clutch members C, C', and a change-speed gear mechanism in casing S and which the chain drive D to a differential gear mechanism in its casing D' on the driving axle,—all of which will be readily understood by those skilled in the art, without particular description.

The radiator R just back of the motor has provided for it a transverse upwardly extending air scoop the under end of which 35 is pitched forward at *a* below the under frame to deflect air upward and rearwardly to the radiator, the scoop having sides *a'* which confine the air from lateral escape.

The forward transverse bar 23 supports 40 an upwardly-extending bracket 27 for holding a post 28 stationary, the upper end of the post being connected to the spring-supporting fork by a distance rod 29 which is pivoted at one end at 30 to that fork and at 45 its other end at 31 to the upper end of the post. This construction steadies the assembled forks above the wheel W against lateral vibratory movements, while permitting the distance rod and its connections vertical 50 movements relatively to the springs 15.

The lower end of post 28, in the present preferred form of this invention, has a tubular foot 32 slanting upwardly and rearwardly, and forming a bearing for the steering post 33; the tubular foot having a bracket portion 34 which is fixed on the transverse bar 21 at 35, and the lower end of the steering post carrying a fixed pinion 36 which is always in mesh with a transverse 60 endwise-movable rack-bar 37 mounted in a way formed between the front edge of the transverse bar 21 and walls of a portion of the bracket portion 34. From each end of this rack-bar a cable 38 runs over an idler 65 39 carried by the front end of a side-bar,

then over an idler 40 carried by a foot of the spring-supporting fork, and thence to an eye 40^a on a rearward side of a wheel-fork foot. By rocking the wheel post, the wheel fork is turned for steering; but the steering may be done if preferred by a device attached to the upper end portion of the wheel fork in a known manner. By the present construction, power is applied, for steering, to points substantially in the plane of the 70 fork-wheel axle, and the steering device is hidden by the fork-wheel hood H. This is the preferred arrangement of the steering mechanism.

To adapt this vehicle for use by sportsmen and others on fishing, shooting or picnic trips, for example, or to provide it with a cover or canopy, each side bar near its front end is provided with a vertical, telescopic post 41, and at its rear end with a 75 post 42 to the upper end of which a supplementary folding post 43 is pivoted at 44.

The upper ends of the post are formed with eyes or otherwise shaped to receive tent or canopy members. In the specific construction, the front wheel hood may be provided with button studs for attachment of the front flap of a tent, and each supplementary folding post is connected by a brace link 46 pivoted to it at 47 with a sliding collar 48 90 on a post 42 to which the link is pivoted at 49, the collar being provided with a set-screw 50. Obviously, the auxiliary folding posts may be turned into an angular upward position with their free ends above and rearwardly of the rear of the vehicle, and thus support a tent or canopy extending over and beyond the rear end of the vehicle, the side and end flaps of the tent being held by 95 ropes and tent-pins. In this way the vehicle may form one end of a camping structure.

The motor axle preferably drives a belt 51 to run a small dynamo 52, and the hood 53 for the radiator, motor and other motive parts has a horizontal case portion 100 54 which can be used to support electric cooking implements detachably connected with the dynamo, which can be thrown into and out of working connection with the motor by a clutch, not shown. The dynamo 55 is supported on a bracket 55 from a side bar under the hood. The dynamo may be used for any desired purposes and can be driven from the motor while the vehicle is stationary by disconnecting the clutches C, C'. 115

To prevent dust and air carried upwardly by the air scoop in front of the radiator from getting inside of the hood 53, a horizontal cover 56 parallel with the cover 54 and spaced apart underneath it, is arranged 120 to form a dust and air exit space extending transversely and discharging through a transverse slot 57 in the rear cover 58 of the body. Cover 58 is shown hinged at 44 and cover 56 is shown hinged to the radiator 125 130

at 59. As it is preferred to make the two-wheeled driving axle the rear axle and to place the motor adjacent such rear axle, the air scoop and dust and air exit described are 5 peculiarly desirable in the present preferred form of motor tricycle because the forward portion of the vehicle shelters the radiator from the air in forward movement of the vehicle and the scoop overcomes the sheltering objection and secures a supply of air, the exit permitting a rearward rush of flow thereof.

Various changes may be made in the form 15 of this invention without departure therefrom. I am the first, so far as I know, to combine with a rockable wheel-fork a spring-supporting and wheel-fork-bearing fork of any kind for sustaining a load-supporting spring or shock absorber at a point below 20 the upper periphery of the wheel carried by the wheel fork, the preferential support being near or below the horizontal plane of the axis of the journal or shaft for such wheel, and this idea may be embodied in 25 various forms.

Advantages of this invention comprise low cost of construction coupled with durability, compactness, a high degree of shock absorption by the front and rear springs 30 extending endwise toward each other from their supports and connected by side bars; and in many cases the feasibility of using solid instead of pneumatic tires on the wheels. By placing the motor with its shaft 35 parallel with the driving axle and by making this axle the rear axle, the motive devices are compactly arranged rearward of the main load. By steering from the wheel-fork feet, the steering devices offer no ob- 40 struction to the view or to the convenience of occupants. This three-wheeled vehicle with its low center of gravity, provided for by having the feet of the spring-supporting fork as low as and preferably below the 45 journal of the wheel carried by the wheel-fork and by the spring suspension of the rear part of the under frame from the rear driving axle structure, and the three-point support of the load on the three wheels, is 50 believed to meet the theoretical conditions that "the three-wheeled carriage, if prop- 55 erly designed, rides as easy as a four-wheeler, or so nearly so that the difference cannot be told by a blindfolded observer riding in the two alternately; while the three-wheeler steers more easily, requires less power to propel, starts and stops more quickly, is simpler, lighter, very much better in mud and appreciably better every- 60 where else." *Self-Propelled Vehicles*, 7th ed., page 69, Audel, New York. Three-wheeled vehicles are less easily upset than four-wheeled vehicles, and are less subject to disintegrating strains on under frame, 65 springs and motor.

Motor cars containing the features of this invention may be driven electrically as well as by other kinds of motive power, and may be made as narrow or as wide, as short or as long, as desired. The location of the 70 feet of the spring-supporting fork near the horizontal plane, or preferably below it, of the journal of the wheel carried by the wheel-fork, effects a simplicity and durability of construction that is desirable be- 75 cause it obviates all bends required in an under frame when such under frame is pivoted to the top of a wheel fork. By the lateral extension of the feet of the spring-sup- 80 porting fork to substantially the full width of the under frame, the side portions of the under frame, that is the side bars with the springs attached to them, are kept approxi- 85 mately parallel throughout their length. Of course the side bars may be connected to the feet of the spring-supporting fork by means of various styles either of springs or of other kinds of shock-absorbers, but the present construction is one designed if pos- 90 sible to eliminate the necessity of pneumatic tires on all three wheels of the vehicles, es- 95 pecially when the vehicle is to be used on fairly smooth roads.

Another advantage is that by bringing the feet of the spring-supporting fork below 25 the journal of the wheel carried by the wheel fork, and so underslinging the under frame relatively to said wheel, the lateral move- 30 ments of such wheel under some conditions of road use are very largely obviated, and 1,00 a common practical objection to motor-tri- 35 cycle construction heretofore obtaining is thereby minimized. This is an important feature, especially when, as above stated, the 40 assembled forks involve the lateral and end- 45 thrust bearings, the lateral bearing of the 50 wheel fork in the spring-supporting fork and adjacent the axle of the fork wheel se- 55 curing a lateral steadiness of the rotating 60 wheel that is most desirable.

What I claim is,—

1. The combination of a wheel fork; a wheel journaled therein; a spring-supporting fork; the wheel fork being journaled in the spring-supporting fork and the lat- 115 ter having laterally projecting opposite spring-supporting feet, and the wheel fork having at each end both end-thrust and lateral bearings in the spring-supporting fork.

2. The combination of a wheel fork; a wheel journaled therein; a spring-support- 120 ing fork; the wheel fork being journaled in the spring-supporting fork and the lat- 125 ter having laterally projecting opposite spring-supporting feet below the axis of the wheel journal, and the wheel fork hav- 125 ing at each end both end-thrust and lat- 130 eral bearings in the spring-supporting fork.

3. The combination of a wheel fork; a wheel journaled therein; a spring-supporting fork; the wheel fork being journaled in the spring-supporting fork and the latter having laterally projecting opposite spring-supporting feet; the free end portions of the wheel fork having bearing feet mounted in bearing recesses in the heel portions of the spring-supporting fork. 70
- 10 4. The combination of a wheel fork; a wheel journaled therein; a spring-supporting fork; the wheel fork being journaled in the spring-supporting fork and the latter having laterally projecting opposite spring-supporting feet; the free end portions of the wheel fork having bearing feet mounted in bearing recesses in the heel portions of the spring-supporting fork; and detachable means for keeping the bearing end portions of the assembled forks together. 75
- 15 5. The combination of a wheel fork; a wheel journaled therein; a spring-supporting fork; the wheel fork being journaled in the spring-supporting fork and the latter having laterally projecting opposite spring-supporting feet; the free end portions of the wheel fork having bearing feet mounted in bearing recesses in the heel portions of the spring-supporting fork; and the wheel-fork-bearing feet being formed with alined holes for the wheel journal. 80
- 20 6. The combination of a wheel fork; a wheel journaled therein; a spring-supporting fork; the wheel fork being journaled in the spring-supporting fork and the latter having laterally projecting opposite spring-supporting feet; the free end portions of the wheel fork having bearing feet mounted in bearing recesses in the heel portions of the spring-supporting fork; and the wheel-fork-bearing feet being formed with alined holes for the wheel journal; the ends of the wheel journal being opposed to walls of the bearing recesses in the heel portions of the spring-bearing fork. 85
- 25 7. The combination of a wheel fork; a wheel journaled therein; a spring-supporting fork; the wheel fork being journaled in the spring-supporting fork and the latter having laterally projecting opposite spring-supporting feet; the free end portions of the wheel fork having bearing feet mounted in bearing recesses in the heel portions of the spring-supporting fork; and the wheel-fork-bearing feet being formed with alined holes for the wheel journal; the ends of the wheel journal being opposed to walls of the bearing recesses in the heel portions of the spring-bearing fork; and means to keep the wheel journal from endwise movement. 90
- 30 8. The combination of a wheel fork; a wheel journaled therein; a spring-supporting fork; the wheel fork being journaled in the spring-supporting fork and the latter having laterally projecting opposite spring-supporting feet; and means supported by the spring-supporting fork for bracing its feet against deformation under load, the wheel fork having at each end both end-thrust and lateral bearings in the spring-supporting fork. 95
- 35 9. The combination with a spring-supporting fork having laterally projecting feet and a bearing at the inner side of its crown and opposite bearings in its heel portions, of a wheel-fork having a bearing at the outer surface of its crown and also having bearing feet; and means for keeping the works in assemblage; the wheel fork being rockable in the spring-supporting fork. 100
- 40 10. The combination of a pair of nested forks; a pin connection for the assembled fork crowns; end bearings for the fork crowns; end bearings for the fork legs; one fork carrying a wheel and the other fork having laterally projecting spring-supporting feet; and means to keep the forks in assemblage. 105
- 45 11. The combination of a wheel fork; a wheel journaled therein; a spring-supporting fork; the wheel fork being journaled in the spring-supporting fork and the latter having laterally projecting opposite spring-supporting feet; a spring fixed to each foot and extending away from the same into connection with one end of a side bar; such side bar; a two-wheeled driven axle; a spring connecting each side bar to the driven axle; and a steering mechanism operatively connected to the wheel fork. 110
- 50 12. The combination of a wheel fork; a wheel journaled therein; a spring-supporting fork; the wheel fork being journaled in the spring-supporting fork and the latter having laterally projecting opposite spring-supporting feet; and a steering mechanism operatively connected to the wheel fork near its wheel journal supporting portion. 115
- 55 13. The combination of a wheel fork; a wheel journaled therein; a spring-supporting fork; the wheel fork being journaled in the spring-supporting fork and the latter having laterally projecting opposite spring-supporting feet; a spring fixed to each foot and extending away from the same into connection with one end of a side bar; such side bar; a two-wheeled driven axle; a spring connecting each side bar to the driven axle; and a steering mechanism operatively connected to the wheel fork; the side bars having cross connections; a motor mounted on the cross-connections with its shaft parallel with the driven axle, and motive connections between the driven axle and transverse motor shaft, said motive connections 120
- 60 125
- 65 130

comprising a clutch, change-speed gear mechanism and differential gear mechanism.

14. The combination of a wheel fork; a wheel journaled therein; a spring-supporting fork; the wheel fork being journaled in the spring-supporting fork and the latter having laterally projecting opposite spring-supporting feet; a spring fixed to each foot and extending away from the same into connection with one end of a side bar; such side bar; a two-wheeled driven axle; a spring connecting each side bar to the driven axle; and a steering mechanism operatively connected to the wheel fork; a transverse connection of the spring-connected side bars; an endwise movable rack; a steering device comprising a pinion working on the rack; and flexible connections between the rack ends and the free end portions of the wheel fork legs.

15. The combination of a wheel fork; a wheel journaled therein; a spring-supporting fork; the wheel fork being journaled in the spring-supporting fork and the latter having laterally projecting opposite spring-supporting feet; and a vertically yielding distance device connected to the assembled forks and constructed for connection with a vehicle frame.

30 16. The combination of a wheel fork; a wheel journaled therein; a spring-supporting fork; the wheel fork being journaled in the spring-supporting fork and the latter having laterally projecting opposite spring-supporting feet; and a vertically yieldable distance device.

17. The combination of a wheel fork; a wheel journaled therein; a spring-supporting fork; the wheel fork being journaled in the spring-supporting fork and the latter having laterally projecting opposite spring-supporting feet; and a steering mechanism comprising a pair of opposite members severally connected with the wheel fork and extending toward a two-wheeled driven axle; and means for operatively connecting the assembled forks.

18. The combination of a wheel fork; a wheel journaled therein; a spring bearing fork in which the wheel fork is rockably mounted, the spring bearing fork having opposite laterally extending feet below the upper periphery of the wheel; a two-wheeled driven axle and means for driving it; a pair of springs severally attached at their end portions to one of said feet and each spring extending from its supporting foot toward the driving axle; a pair of springs spaced laterally apart, secured to the driving axle

60 structure and extending therefrom toward the assembled forks; bar connections between each pair of side springs; transverse connections; a vehicle body mounted on the bars; a distance rod connecting the assembled forks and frame; and a steering mech-

anism operatively connected with the rockable wheel fork.

19. The combination of a wheel fork; a wheel journaled therein; a spring bearing fork in which the wheel fork is rockably mounted, the spring bearing fork having opposite laterally extending feet below the upper periphery of the wheel; a two-wheeled driven axle and means for driving it; a pair of springs severally attached at their end portions to one of said feet and each spring extending from its supporting foot toward the driving axle; a pair of springs spaced laterally apart, secured to the driving axle structure and extending therefrom toward the assembled forks; bar connections between each pair of side springs; transverse connections; a vehicle body mounted on the bars; a distance rod connecting the assembled forks and frame; and a steering mechanism operatively connected with the rockable wheel fork, such mechanism comprising steering members extending from the steering fork in the direction of the driven axle and also comprising means for operating said members to turn the steering fork.

20. The combination of a wheel fork; a wheel journaled therein; a spring bearing fork in which the wheel fork is rockably mounted, the spring bearing fork having opposite laterally extending feet below the upper periphery of the wheel; a two-wheeled driven axle and means for driving it; a pair of springs severally attached at their end portions to one of said feet and each spring extending from its supporting foot toward the driving axle; a pair of springs spaced laterally apart, secured to the driving axle structure and extending therefrom toward the assembled forks; bar connections between each pair of side springs; transverse connections; a vehicle body mounted on the bars; a distance rod connecting the assembled forks and frame; and a steering mechanism operatively connected with the rockable wheel fork, such mechanism comprising steering members extending from the steering fork in the direction of the driven axle and also comprising means for operating said members to turn the steering fork; a motor mounted adjacent the driving axle with its shaft parallel therewith; a clutch and change-speed gear mechanism for said shaft; a differential gear mechanism for said driving axle and a driving connection between the axle and the differential gear.

21. The combination of a wheel fork; a wheel journaled therein; a spring bearing fork in which the wheel fork is rockably mounted, the spring bearing fork having opposite laterally extending feet below the upper periphery of the wheel; a two-wheeled driven axle and means for driving it; a pair of springs severally attached at

- their end portions to one of said feet and each spring extending from its supporting foot toward the driving axle; a pair of springs spaced laterally apart, secured to 5 the driving axle structure and extending therefrom toward the assembled forks; bar connections between each pair of side springs; transverse connections; a vehicle body mounted on the bars; a distance rod connecting 10 the assembled forks and frame; and a steering mechanism operatively connected with the rockable wheel fork, such mechanism comprising a pair of steering members one attached to the wheel fork at one side of its 15 upright central axis and the other attached to the wheel fork at the other side of such axis; a transverse member to which the steering members are attached; and a steering post operatively connected with the 20 transverse member.
22. The combination of a wheel fork; a wheel journaled therein; a spring-supporting fork in which the wheel fork is rockably mounted; a steering mechanism connected with the wheel fork; the spring-supporting fork having opposite laterally-projecting feet below the axis of the wheel journal; a two-wheeled driven axle; a pair of springs spaced apart and suspended from 25 the driven axle structure; a pair of springs, one attached to one and the other to the other of said feet; and side bar connections between said springs; the steering mechanism comprising a member secured to the 30 wheel fork to rock it for steering and extending in the direction of the driven axle; means to control lateral vibration of the assembled forks; and accessible to the driver a steering device operatively connected to 35 said member.
23. The combination of a wheel fork rotatably mounted in a spring-supporting fork having oppositely laterally extending feet near the axis of the wheel carried by 40 the wheel fork; a shock-absorber connected to each foot; a side bar one end of which is attached to each shock-absorber; each side-bar having at its other end opposed to its upper side, a lengthwise-extending spring 45 operatively connected to the side bar; and a two-wheeled driving axle from which the last-mentioned springs are suspended; a motor and motive devices elastically supported by the spring-carrying end-portions 50 of the side-bars; and operative connections between said motive devices and the driving axle.
24. The combination of a pair of forks, one journaled lengthwise in the other; a 55 wheel journaled in one of the forks; a shock-absorbing under-frame connecting the other fork with a two-wheeled driving axle; and such driving axle.
25. The combination of a pair of forks,

one journaled lengthwise in the other; a 65 wheel journaled in one of the forks; a shock-absorbing under-frame connecting the other fork with a two-wheeled driving axle; and such driving axle; the shock-absorbing frame connection with the fork being below the upper periphery of the wheel 70 carried by the fork.

26. The combination of a pair of forks, one journaled lengthwise in the other; a 75 wheel journaled in one of the forks; a shock-absorbing under-frame connecting the other fork with a two-wheeled driving axle; and such driving axle; the shock-absorbing frame connections with the fork being near the horizontal plane of the axis of 80 the fork wheel.

27. The combination in a three-wheeled vehicle of a single-wheel support; a spring-supporter; a two-wheeled support; a four-cornered under-frame comprising at each 85 corner portion a spring extending in the direction of the length of the under frame, one pair of springs being secured to the spring-supporter and the single-wheel support being rockable for steering relatively 90 to the single wheel support; and the other pair of springs being connected with the two-wheeled support; the under frame being supported about in a plane passing through the three wheel centers; and the inward portion of the single wheel rotating 95 and being shiftable laterally intermediate side members of the under frame.

28. The combination of a two-wheeled driving axle; an under frame yieldingly 100 connected with the driving axle; a wheel fork and wheel carried thereby; and a fork in which the wheel fork is rockably mounted for steering, the latter fork having a yielding connection with the under frame 105 and such connection being below the journal of the wheel carried by the wheel fork.

29. The combination of a wheel fork; a spring-supporting fork in which the wheel fork is rockable for steering, the spring-supporting fork having opposite, laterally-projecting feet below the journal for the wheel carried by the wheel fork, and the assembled forks having end-thrust bearing surfaces; a spring attached at one end to 110 each foot and projecting toward a two-wheeled driving axle; said two-wheeled driving axle; a pair of side bars each attached at one end to an end of one of the projecting springs; a spring connection between the driving axle and each side-bar; a vertically yielding distance rod mechanism 115 connecting the upper portion of the spring-supporting fork with a rigid portion of the frame and constructed to restrain lateral tipping of the assembled forks; and means for rocking the wheel fork for steering.

30. The combination of a wheel fork, a

spring-supporting fork, and a wheel journaled in the wheel fork, the wheel fork being journaled in the spring-supporting fork and having therein an end-thrust and lateral bearing near the wheel journal.

5 In testimony whereof I have hereunto

set my hand in the presence of two subscribing witnesses.
